(57) CLAIM

The ornamental design for a ring box with engraving plate as shown and described.

DESCRIPTION

FIG. 1 is a perspective view of a ring box with engraving plate;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a left side elevation view thereof, the right side elevation view being a mirror image.

The broken lines in the drawings depict portions of the ring box with engraving plate that form no part of the claimed design.
